CARD FILING DEVICE

Filed Dec. 27, 1923

John Q. Sherman INVENTOR.

BY

Ascent & Lee ATTORNEY.

UNITED STATES PATENT OFFICE

JOHN Q. SHERMAN, OF DAYTON, OHIO, ASSIGNOR, BY DIRECT AND MESNE ASSIGNMENTS, TO THE STANDARD REGISTER COMPANY

CARD-FILING DEVICE

Application filed December 27, 1923. Serial No. 683,068.

My invention relates to devices for use in card filing systems, and more particularly to structures and devices whereby a very compact, and quickly available means is provided for the filing of and removal from the files of desired cards, folders, or envelopes containing other papers.

It is my object to provide in as simple a manner as possible for the housing of a large number of cards, envelopes, etc., within a cabinet, and more particularly it is my object to provide for a series of card or envelope holders permanently secured within a cabinet, but rendered individually available in a simple manner.

It is my object to provide on the holders, identifying marks, which are also finger holds and to use in connection with the cabinet, a chart or index whereby the operator can quickly determine the number of the holder in which will be found the card or envelope that he wishes, and will then select the desired finger hold, and by means of it will move the holder to a position to expose the card. Each holder will contain a number of cards, arranged with staggered exposures, to permit of easy selection of the card desired.

Another object of my invention is to provide an index located in a convenient point with relation to the cabinet, such as on the door thereof. Another object is to provide a door or lid for the cabinet which acts as a writing support or desk for making entries upon the cards. In crowded offices this desk-cover arrangement is very valuable.

Another object of the preferred embodiment of my invention is to provide for the full length projection of the identifying finger holds from the body of the holders, and to provide by means of the swinging door or lid for sufficient clearance for the extending elements.

The above objects and other advantages to be noted, I accomplish by that certain construction and arrangement of parts to be hereinafter more specifically pointed out and claimed.

In the drawings:

Figure 1 is a perspective view of one form of the device when in use.

Figure 2 is a central longitudinal section of the device.

Figure 3 is a perspective view from the side of the cabinet with the door open and one of the holders withdrawn for use.

Figure 4 is a perspective view of a preferred form of holder.

In the preferred form of cabinet I have provided a metal box 1 with a false bottom 2, preferably screwed to the walls of the box, and with one end of the box open as at 3.

At the open end of the box is mounted a door 4, which is preferably arranged to be hinged at the base of the box, and is provided with a bolt plate 5, which engages the bolt element of a lock 6 on the top of the box. This door is preferably formed with an elevated margin 7, which abuts against the walls of the box surrounding the opening therein to hold the body of the door away from the open end of the box.

The false bottom of the box is formed with a series of guide slots for card holders and at the rear at the ends of the slots, holder retaining shoulders 8 are formed, the purpose of which will be described below.

As it will be found convenient to use the door as a writing support for making entries on the cards, I preferably provide the door with the disappearing arc shaped arm 9 pivotally mounted at one end to the margin 7, said arm passing through slot 10 formed in the flange 11 of the box at the open end. This will relieve the hinges of the door from the strain resultant upon the use of said door as a writing support.

It will also be noted that the key chart for the device can best be located on the inner face of the said door, said chart being indicated at 12 thereon. A pair of thin strips 13 mounted across the inner face of the door 4 serves to hold the chart in place.

As will be noted the chart is arranged with alphabetical sections, with the key numbers entered opposite the names, by the operator at the time that he enters the names.

The holders in preferred form are made of thin sheet metal having bodies 14, of pref-

erably the length of the cards or envelopes to be mounted therein, and are folded back on themselves at 15, to hold the cards snugly in place.

8 The cabinet will be of a size to retain the holders with their edges in a single plane at the box opening.

10 Naturally there will be a wide variation possible in forming the holder. I prefer, however, to form them as described and shown and to form a tongue 16 at the inner end of the lower edge of each holder.

15 I form out tongues of metal 17, at staggered positions on the holders for the several numerals applied as identifying marks pref-

erably for both faces of the tongues, or in some other way I provide the holders with extending tongues, which project beyond the forward edges of the holders. The top flange

20 18 above the opening in the box will preferably be cut with interspaced kerfs, one for each holder, and the holders will be set into the box with their top edges spaced and given a slight frictional grasp by the kerfs, and

25 with the tongues 17 extending outwardly.

As shown in Figure 2 the top of the box also has a false top with slots and shoulders corresponding with the slots and shoulders in the false bottom. Tongues similar to those ex-

30 tending out at the bottom of the holder also extend out at the top, and the shoulders at the ends of the guide slots in the false top limit the outward movement of the holders at the top.

35 The holders will rest in horizontal position on the false bottom of the box, and the tongues 16 on the back edges of the holders will lie behind the shoulder 8 of the false base plate, so that the holders cannot be removed from the box without unscrewing the false base bottom, and taking the structure to pieces. This is only a preferable form, chosen to give best service by preventing the tampering with the holders, or removal

45 thereof, so as to make the device foolproof.

40 The door when closed will have sufficient clearance to fully clear the projecting tongues 17, and as noted the tongues are arranged in a series of slanting rows of vertical tendency across the face of the assembly. The tongues 17 will also be marked with numerals, or other designating marks to correspond with the index or chart.

45 I have shown cards 19 which will fit within the confines of the bodies of the holders, and will have portions of varying length cut away from the front edges thereof, so as to expose a portion 20 of each card, when the holder is filled. The exposed portions of the 60 cards will bear indicating marks and the exposures in the preferred form will be in staggered relation similar to the index tabs on the holders.

Considering the device as filled with hold-

ers, and cards in the holders, the use thereof will be as follows: the operator will open the door, and consult the name on the chart on the inside of the door for the key number of the holder in which the card he desires is to be found. He then picks out the tongue 17 bearing the key number and pulls out the holder as far as it will go. This will make the card that is sought, available to the operator, and he can see from the exposure thereof which one it is, in the holder, and will withdraw it to make his entry. In making the entry he can lay the card on the inside of the door, and jot down his entry whereupon he will replace the card and push the holder back in place.

It may be observed of this simplest, and I believe most readily operable form of my invention, that the operator is not required to finger over a number of cards to find the one he wants, and a little familiarity with the arrangement of numbers on the holders, and with the chart will enable him to select the desired card rapidly with the least possible disturbance to other holders or other cards. Every individual card can be given an ample exposure so as to be visible at once, when the holder is withdrawn, and furthermore, ample space is provided for the indicators or tabs on the holders, so that the selected one can be grasped in the fingers.

The great advantage of sliding the holders out horizontally is that it requires a minimum of mechanism, and the holders stay out without dropping away, because they are held in place by the flange of the false bottom.

It will be evident that other forms can be provided which will still embody the features set forth above, and I do not wish to be construed as having limited myself by the above description to other than the full range of mechanical equivalents of the parts named.

Having thus described my invention, what I claim as new and desire to secure by Letters Patent, is:

1. A filing cabinet, comprising an open ended box having a hinged lid and turned up edges of the lid providing clearance between said lid and the plane of the edges of the box, a series of holders in said box slidable edge-wise in vertical planes, said holders formed of plates with return bent portions for retaining a plurality of record papers, means for limiting the slidable movement of each of said series of holders, said holders having cut away portions adjacent the plane of said edges of said box, record papers of such size as to be retainable within said holders, said papers having indicia arranged in staggered relation in vertical planes so as to be readily accessible for use with the withdrawal of the respective holders from said box, and indicia on said holders extending beyond the plane of the edges of the box.

2. A filing cabinet, comprising an open ended box having a hinged lid and turned up

edges of the lid providing clearance between said lid and the plane of the edges of the box, a series of holders in said box slidable edge-wise in vertical planes said holders formed of plates with return bent portions for retaining a plurality of record papers, means for limiting the slidable movement of each of said series of holders, said holders having cut away portions adjacent the plane of said edges of said box, record papers of such size as to be retainable within said holders, said papers having indicia arranged in staggered relation in vertical planes so as to be readily accessible for use with the withdrawal of the respective holders from said box, and indicia on said holders extending beyond the plane of the edges of the box, and means of limiting the opening movement of said lid to a horizontal plane.

20 3. A filing cabinet, comprising an open ended box having a hinged lid and turned up edges of the lid providing clearance between said lid and the plane of the edges of the box, a series of holders in said box slidable edge-wise in vertical planes, said holders formed of plates with return bent portions for retaining a plurality of record papers, means for limiting the slidable movement of each of said series of holders, said holders having cut away portions adjacent the plane of said edges of said box, record papers of such size as to be retainable within said holders, said papers having indicia arranged in staggered relation in vertical planes so as to be readily accessible for use with the withdrawal of the respective holders from said box, and indicia on said holders extending beyond the plane of the edges of the box, and a key chart for said holders and papers retained on said lid.
